E. N. DOLLIN

FIRE EXTINGUISHER

Filed April 21, 1920

INVENTOR
E.N. Dollin

UNITED STATES PATENT OFFICE.

EDGAR N. DOLLIN, OF SYRACUSE, NEW YORK.

FIRE EXTINGUISHER.

Application filed April 21, 1920. Serial No. 375,540.

To all whom it may concern:

Be it known that EDGAR N. DOLLIN, of Syracuse, in the county of Onondaga, in the State of New York, have invented new 5 and useful Improvements in Fire Extinguishers, of which the following, taken in connection with the accompanying drawings, is a full, clear, and exact description.

This invention relates to certain improvements in hand fire extinguishers involving the use of a bottle or analogous container for the fire extinguishing fluid, such as carbon tetra-chloride, and a secondary collapsible and expandable container for normally 10 separated gas producing elements, which, when liberated in the presence of each other, causes the inflation of the secondary container to such an extent as to displace practically the entire contents of the first named 15 container through the discharge opening thereof.

The main object is to provide a simple, economical and highly efficient hand fire extinguisher by which a continuous stream of 20 the fire extinguishing liquid may be projected from the container by the automatic inflation of an expandable sack or container through the combining of normally separated gas producing elements confined therein, 25 but liberated in the presence of each other by the voluntary act of the operator, thereby avoiding the use of pumps and analogous devices which produce intermittent or pulsating streams.

Another object is to provide means whereby practically all of the fire extinguishing fluid may be gradually expelled by the inflation of the sack without liability of closing the outlet or cutting off communication 30 between different parts of the container.

A further object is to make the sack, and also the confining mediums for the gas producing elements contained therein, of paper or other comparatively inexpensive material 35 treated in such manner as to render them impervious to their respective contents and fire extinguishing fluid without liability of impairment by said contents, so that the entire device may remain charged ready for 40 use for an indefinite period of time.

Other objects and uses relating to specific parts of the device as a whole will be brought out in the following description.

In the drawings:

Figure 1— is a longitudinal vertical section of a hand fire extinguisher embodying

the various features of my invention, a portion of the inflatable sack being broken away to show the confining media for the gas producing elements. 60

Figure 2— is a transverse sectional view taken in the plane of line 2—2, Figure 2—1—.

Figure 3— is an elevation of the detached inflatable sack showing the portion thereof surrounding the stopper in section. 65

Figure 4— is an elevation of the detached confining media for the gas producing elements, broken or mutilated to liberate 70 said elements in the presence of each other within the sack.

As illustrated, this fire extinguisher comprises a container 1— for the fire extinguishing fluid, as 2—, a secondary expandable and contractile container 3— 75 within the container 1—, and one or more (in this instance 2) confining media 4— for gas producing elements, which, together with a quantity of liquid, as water, 5—, are confined within the secondary container 80 3—.

The container 1— is preferably made in the form of a bottle of glass or other comparatively inexpensive material which is impervious to the fire extinguishing liquid contained therein, and is provided at one end with an inlet opening 6— for filling purposes, and at its opposite end with a relatively small nozzle 7— having a correspondingly small outlet 8— for the discharge of the fire extinguishing liquid there-through. 85

The inlet opening 6— is normally closed by a stopper 9— of cork or other suitable material, which is held in place by a cap 10— having its edges 11— crimped around and under a bead, as 12—, surrounding the mouth of the bottle. 90

The outlet 8— is also normally closed by a stopper 13— of cork or other suitable material, and held in place by a similar, but smaller cap 14— crimped around a suitable bead 15— on the end of the nozzle 7—. A wire or similar rod 16— 100 is passed centrally through the stopper 8— and has its inner end provided with a shoulder 17— engaging the adjacent end of said stopper, while its outer end is provided with a ring 18— by which the bottle may be suspended in a vertical position upon a nail or equivalent support when not in use. The cap 14— is made of relatively 105

light and easily bendable material either of extreme thin metal or heavy paper, which will permit the withdrawal of the stopper and cap by an outward pull upon the ring 5—18—, but is of sufficient strength to support the bottle when suspended by said ring.

The cap —10— covering the larger opening —6— is made of heavier material, such as sheet metal, and is of sufficient strength 10 to resist the pressure of the gases within the sack —3— acting upon the cork —9— when the gas producing elements are liberated by the disintegration of the confining media —4— as hereinafter more fully described.

15 One end of the sack —3— is open and preferably extends through the inlet opening —6— around the cork or stopper —9— and is preferably overturned on the outer end of the mouth of the bottle to be engaged 20 and held in place by the cap —10— and cork —9—, both of which constitute a support for suspending the sack within the bottle and effectively closes the open end of the sack, thereby affording an inexpensive and 25 convenient means for holding the sack within the bottle.

This sack is preferably made of tough, but highly flexible paper, treated with shellac or other suitable material to render it 30 impervious to its contents or to the surrounding fire extinguishing fluid, and is normally compressible by folding or twisting to a size or diameter sufficiently small to enable it to be inserted through the opening 35 —6— into the bottle, where it is suspended by the cork —9— and cap —10—, its surface area when distended or inflated being equal to and preferably greater than that of the interior of the bottle to enable all portions thereof to contact with all portions of the walls of said bottle in order to assure the expulsion of all of the fire extinguishing fluid when the sack is inflated.

40 The confining media for the gas producing elements preferably consist of relatively small tubes of thin but tough paper or equivalent inexpensive material coated with shellac or similar substance to render them impervious to the surrounding body —5— 45 of water, and are closed at both ends, said tubes being separate and adapted to confine therein suitable quantities of gas producing elements, such as sodium-carbonate in one tube and tartaric acid in the other tube, which elements, when liberated in the 50 presence of each other and in the body of water —5—, produce a highly expandable gas which will immediately inflate the sack —3— against all portions of the walls of the bottle —1— for expelling the fire extinguishing fluid through the discharge nozzle —7— when the stopper —8— is removed.

55 It is, of course, necessary to break or disintegrate the tubes —4—, and, for this purpose, relatively small wires —19— are

60 passed centrally through the tubes and provided at one end with sheet metal cutters —20—, while the opposite ends are preferably twisted together and passed through a central opening —21— in the cork —9— and cap —10—, and are engaged by an external finger ring —22—.

The ends of the tubes —4— are sealed 65 around the adjacent portions of the wires —19— to confine the gas producing elements therein. When it is desired to use the device for fire extinguishing purposes, the bottle is taken in one hand and the wires —19— are pulled out endwise through the opening —21— by means of the ring —22— thereby bringing the ends of the tubes 70 against a metal abutment —23— on the inner face of the cork, and by a continued pull upon the wires, causes the central portions of the tubes to burst under the pressure 75 produced by the engagement of the cutter —20— against the inner ends of the tubes, or the cutters may be drawn through the tubes to cut or tear the same sufficiently to liberate the contents of said tubes.

80 Either just preceding or immediately following the disintegration of the tubes, the cork —8— is withdrawn to allow the exit 85 of the fire extinguishing fluid through the nozzle —7—, which may be directed upon the fire to be extinguished, it being understood that as soon as the gas producing elements are liberated in the presence of each other, the sack —3— is immediately expanded 90 against the walls of the bottle, thereby causing the expulsion of the fire extinguishing liquid through the nozzle —7— in a continuous stream.

95 In order to maintain a sufficient opening or 100 openings between the sides of the sack and walls of the container —1— when the sack is inflated, suitable coils —24— of wire or equivalent material are attached by any suitable fastening means to one or more sides 105 of the sack to prevent the adjacent portions 110 of the sack from contact with said walls, thereby establishing passages from end to end of the bottle through which the liquid 115 may be discharged even though all other portions of the sack may be engaged with said walls.

120 It is evident, however, that instead of making the sack —3— and tubes —4— of paper, they may be made of comparatively inexpensive cloth, such as cotton treated in such manner as to render it impervious to the liquids which may contact therewith, and, therefore, I do not wish to limit myself 125 to the use of any particular material, nor to the exact structural details as shown and described, nor to the use of any particular gas producing element or elements either physically or chemically combined.

130 What I claim is:

1. A fire extinguisher comprising a bottle

- having an inlet in one end and an outlet in its opposite end and containing a fire extinguishing fluid, stoppers for the inlet and outlet, a normally deflated inflatable bag 5 within the bottle having an inlet end secured in the inlet of the bottle and containing a gas-producing element, an hermetically sealed cartridge within the bag and containing another gas-producing element, whereby the bottle with the bag and cartridge therein may be inverted and held 10 in any position without liberating any of the gas-producing elements, and means, operable at will, for disintegrating the cartridge 15 to release its contents in the presence of the other gas-producing element in the bag for generating gas in said bag and thereby expanding the same to expel the fire extinguishing fluid from the bottle when the 20 stopper in the outlet is open, and means for holding portions of the bag out of contact with the walls of the bottle when the bag is expanded to maintain a passage-way for the liquid from all portions of the bottle to 25 the outlet.
2. A fire extinguisher comprising a container for a fire extinguishing fluid having an inlet and an outlet, stoppers for said inlet and outlet, a non-elastic inflatable bag with- 30 in said container and containing a gas producing element, means for confining additional gas producing media within the bag separate from the contents thereof in all
- positions of adjustment of the fire extinguisher, and means, operable at will, for liberating said gas producing media from its confining means in the presence of the gas producing element in the bag for generating gas within and expanding said bag to expel the fire extinguishing fluid from the container when the outlet is opened, and means for holding portions of the bag out of contact with the walls of the bottle when the bag is inflated to maintain a passageway for the liquid from all portions of the bottle 35 to the outlet.
3. A fire extinguisher comprising non-communicating chambers one within the other, one of the chambers containing a fire extinguishing fluid, and provided with an 40 outlet, the other chamber having normally contracted expandable walls, means under the control of the operator for causing the expansion of said walls to expel the fluid from the first named chamber through its outlet, 45 and means for holding portions of the expandable walls in spaced relation to adjacent portions of the walls of the other chamber when said expandable walls are distended.

In witness whereof I have hereunto set 50 my hand this 16th day of April, 1920.

EDGAR N. DOLLIN.
